UNITED STATES PATENT OFFICE.

FRANK B. WHEAT, OF LOS ANGELES, CALIFORNIA.

SECTIONAL PARTITION OR PANEL STRUCTURE.

Application filed December 10, 1926. Serial No. 153,977.

This invention relates to partition or panel structures which are made up of a plurality of sections whose meeting edges are adapted to be concealed by pilasters, said sections and 5 pilasters being so interlocked as to permit the same to not only be readily assembled but to also permit them to be disassembled. For this reason the partition or panel structure of the present invention might be 10 termed a portable one.

One object of the present invention is to provide a sectional partition wherein the same elements which serve to lock the pilaster to the meeting edges of two sections also 15 serve the purpose of locking said two sections together.

A further object of the invention is to provide the partition sections and pilasters with interlocking elements which lie either 20 flush with or below the surfaces of the partition members whereby said members may be conveniently packed for transportation. Further, by having the locking elements 25 lying at least flush with the surfaces of the partition sections or pilasters, there is no danger of said locking elements becoming damaged or rendered unusable during transportation.

Another object of the invention is to provide a form of interlocking means between 30 the pilaster and the partition sections which will permit the pilaster first assembled against the partition to be simply placed against said partition and the interlocking 35 elements then brought into locking engagement. This renders it unnecessary to move the pilaster vertically or longitudinally of itself when it is being assembled. Of course, the pilaster last assembled on the opposite 40 side of the partition must be moved vertically when assembling it against the partition sections.

In the accompanying drawings:—

Figure 1 is an elevational view of a 45 sectional partition embodying the present improvements.

Fig. 2 is a vertical sectional view through the partition showing the pilasters locked in place.

Fig. 3 is a horizontal sectional view 50 through a portion only of a partition showing the meeting edges of two partition sections and the pilasters locked in place.

Fig. 4 is a detail view of one of the 55 partition sections showing the position the lock-

ing elements thereon are adapted to occupy 60 previous to assembly.

Fig. 5 is a vertical sectional view similar 65 to Fig. 2 showing a partition or panel where a pilaster is used on one side only of the partition or panel.

Fig. 6 is a detail illustration of the locking 70 elements carried by the partition sections and the pilasters.

The partition may, of course, be of any 75 desired length, but, in the present instance, it is only necessary to describe two juxtaposed sections in order to fully disclose the invention. In the accompanying drawings the joint formed between the meeting edges of two juxtaposed sections 10 is adapted to 80 be concealed by a pilaster 11 overlying the joint at one side of the partition and by the pilaster 11^a on the opposite side. The locking means for securing the pilasters to the two sections 10 are also utilized for locking 85 the two partition sections themselves together. In the present instance, this is accomplished by having locking elements secured to the meeting edge of each partition section 10 adapted to project into recessed portions in the pilasters and there interlock with locking elements on said pilasters whereby the interlocked locking elements 90 on the sections and pilasters firmly secure the pilasters to the sections, and those portions of the locking elements on the sections which project into the recessed portions of the pilasters serve to prevent movement of the two sections 10 away from each other.

In the preferred form the locking elements on the edges of the sections 10 consist of a plate 12 pivotally secured to the sections 10 and said plates are formed with hook members 13 which serve as latches 95 adapted to engage behind locking plates 14 on the pilasters, the pilasters being recessed adjacent each interlocking plate so as to permit the hook portions 13 of the plates 12 to engage behind said locking plates 14. Previous to assembly of the partition the locking elements 12 on the partition sections 10 are adapted to lie in a position where they will be located flush with or beneath the side surfaces of said partitions as shown in Fig. 4. When the partition is being assembled the two sections 10 are properly placed together and a pilaster is then positioned over the joint formed at the meeting edges of said sections. The locking elements 12 are then 100 105 110

turned on their pivotal centers so that the hook members 13 at one end thereof engage behind the locking plates 14 on said pilaster. Assuming the pilaster 11 shown in Fig. 2 to 5 be the first one to be assembled, pilaster 11 is then placed against the opposite side of the partition with its locking plates 14 slightly above the protruding hook members 13. The pilaster is then lowered so that said 10 hook members engage behind the locking plates 14 thereon. In this way the two pilasters are firmly locked to the partition section and by reason of the protruding hooked ends 13 of members 12 projecting into the recessed 15 portions of the pilasters the partition sections themselves will also be firmly locked together. In this connection, it will be understood that each of the meeting edges of the two panel sections carry similar locking 20 members 12, the members on one section being positioned intermediate the members 12 on the other section vertically of the joint formed by the two sections. In other words, alternate locking members 12 are on the edge 25 of one section 10 and the other alternate locking members 12 are on the edge of the other section 10, the total number of locking members on the two sections corresponding to the number of locking plates 14 on one pilaster. 30 It will be understood, of course, that the present invention is also adapted for use in panels as well as in partitions. It can also be used for counter fronts or for panel wainscoting or in other similar instances 35 where a pilaster is used only on one side. Where such use is made of the invention the locking plate 14 is screwed or attached to the concealed face of each two juxtaposed panel sections so as to engage the hook members 13 at one end of the locking members 12 carried by said panel sections. In instances such as these the hook members 13 are first turned to their lateral position and the 40 pilasters which are to be used for moving the joint at the front of the counter front are then placed over the protruding hook members 13 of the locking members 12. 45 In either instance the pilaster or pilasters will be originally locked in place and by 50 reason of the fact that each of the two meeting edges carry locking members 12, the sections themselves will be firmly locked together. Other advantages consist in the 55 lower costs of production of the locking elements and not only are such locking elements of plain and strong construction but they are also so arranged on the panel or partition sections and on the pilasters that they 60 cannot very easily be damaged prior to assembly.

What I claim is:

1. A sectional partition or panel structure comprising two juxtaposed sections, a pilaster separable from the sections and overlying the joint between said sections, and

means for securing said pilaster to said sections, said means also serving as a lock for securing said two sections together.

2. A sectional partition or panel structure comprising two juxtaposed sections, a pilaster separable from the sections and overlying the joint between said sections, and cooperating locking elements on said pilaster and sections for locking said pilaster to said sections and for locking said two sections together.

3. A sectional partition or panel structure comprising two juxtaposed sections, a pilaster separable from the sections and overlying the joint between said sections, catches on said pilaster and cooperating latches on said sections for locking said sections together and for locking said pilaster to said sections.

4. A portable sectional partition structure comprising two juxtaposed sections, a pilaster overlying the joint between said sections at one side of the partition, cooperating locking elements on said sections and pilaster securing said pilaster to said sections, and a pilaster on the opposite side of the partition overlying said joint, said last mentioned pilaster being secured to the partition by the locking elements on said sections.

5. A portable sectional partition comprising two juxtaposed sections, pilasters at opposite sides of said partition overlying the joint between said sections, a pair of locking elements on each pilaster, and a locking element on each partition section, the locking element on each section engaging one locking element of each pilaster.

6. A sectional partition comprising two juxtaposed sections, a pivoted locking element on each section, a pilaster on each side of the partition overlying the joint between said sections, and locking elements on said pilasters, the pivoted locking elements being adapted to be turned into locking engagement with the cooperating elements on the pilaster first assembled against the partition and the pilaster last assembled against the partition being adapted to be moved longitudinally of the joint to bring its locking elements into engagement with the locking elements on said sections.

7. A sectional partition comprising two juxtaposed sections, locking elements on the meeting edges of said sections and capable of lying beneath the side surfaces of said sections, a pilaster overlying the joint between said sections and locking elements on said pilaster, the locking elements on said sections being pivoted whereby they may be turned into interlocking engagement with the elements on the pilaster.

8. A sectional partition comprising two juxtaposed sections, a pilaster overlying the joint between said sections, locking elements

on said pilaster, and pivoted locking elements on each of the meeting edges of said sections adapted to be turned on their pivotal centers into engagement with the locking elements on the pilaster.

9. A sectional partition comprising two juxtaposed sections, a pilaster overlying the joint between said sections, locking elements on said pilaster, and pivoted locking ele-

ments on each of the meeting edges of said sections adapted to be turned on their pivotal centers into engagement with the locking elements on the pilaster, said pilaster being recessed to receive said pivoted locking members, said pivoted locking members co-operating with said recessed pilaster to lock the two partition sections together.

FRANK B. WHEAT.
